UNITED STATES PATENT OFFICE.

DANIEL B. LUTEN, OF INDIANAPOLIS, INDIANA.

MASONRY AND REINFORCED-CONCRETE STRUCTURE.

1,048,843.

Specification of Letters Patent. Patented Dec. 31, 1912.

Application filed May 6, 1907. Serial No. 372,147.

To all whom it may concern:

Be it known that I, DANIEL B. LUTEN, a citizen of the United States, residing at Indianapolis, in the county of Marion and State of Indiana, have invented new and useful Improvements in Masonry and Reinforced-Concrete Structures, of which the following is a full, clear, concise, and exact description, reference being had to the accompanying drawing, forming a part of this specification.

My invention relates to improvements in masonry and reinforced concrete structures applying more particularly to abutments and wings for bridges in which a high springing and clearance is desired with efficiency in resisting the thrust of the earth fill and the weight or thrust of the structure.

This invention has for its object the providing of a durable and efficient structure of handsome appearance suited to the needs of street crossings where a high springing and clearance are required at the ends of the span.

Another object is to provide an efficient reinforced abutment or wing near the end of the span capable of resisting the pressure of the earth behind it with a minimum of material; and finally, by combining this abutment or wing with a horizontal member, to resist the thrust of the arch or bridge and thus reduce the amount of material required in the abutments, thus further increasing the efficiency of the structure.

These several objects will be readily understood upon reference to the accompanying drawings illustrating my invention in the preferred forms and the constructions of its several features, wherein:

Figure 1 is a longitudinal sectional view taken on the center line of the bridge; Fig. 2 is an elevation of the same structure showing one arrangement of wing and spandrel wall to conform to the section shown in Fig. 1; Fig. 3 is a transverse section taken on the dotted line 3-3 of Fig. 2, looking toward the abutment; Fig. 4 is a modification of Fig. 2, accomplishing the same purpose of supporting the earth filling within a part

of the span, but with the wing separated from the arch, or bridge proper; Fig. 5 is a transverse section on the line 5-5 of Fig. 4; Fig. 6 is a longitudinal section showing a modified form of the abutment shown in Fig. 1; Fig. 7 is a plan of a bridge abut-

ment and wings showing the arrangement of the reinforcement to resist the earth pressure; Fig. 8 is a longitudinal section of a similar arch in which the same result is accomplished in a modified manner.

Fig. 1 of the drawings shows in section part of an arch bridge extending from bank 1 to the pier 2 and provided with an abutment consisting of ribs 4 and 5 which converge toward the springing line and which terminate in a transverse footing 3. This abutment is built by first laying the lower rib 4 on the previously excavated earth foundations, then covering that rib with earth to form a bed for the upper rib 5 which is then laid on the earth filling 6. In order to secure a high springing suitable for street crossings, a false bench wall 7 is extended from the springing downward. It may be attached to and carried by the arch, (Fig. 6) or may be built on a separate footing (Fig. 1) and is adapted to give the intrados of the arch a high springing point without the use of the mass of masonry in the abutment that would be required if the abutment and bench wall were cast in one solid piece. The bench wall may be extended beyond the face of the arch in wings such as 7^a to hold the toe of the slope and earth filling allowed to fill in behind the wings and bench wall to partly fill the opening behind the wall. The arch will then appear to have a solid abutment except for the slight line of junction along the springing. The part above the junction line 12 is in the form of a projection 11 extending below the surface 19 of the arch and having a sharper curvature 20 to make the lower surface of the arch conform to the face of the wall 7. There results an arch of handsome appearance as shown in Fig. 2 with oval curve and high springings, yet in which the wall 7 and wings 7^a are independent from the body of the arch and supported on separate foundations.

The reinforcing rib shown in Fig. 1 and in Fig. 3 consists of pairs of angles 8 and 9 following the intrados and extrados respectively. The pairs of angles are joined by web lacing bars 10. At the left of Fig. 1 the rib is shown extended into the abutment to secure anchorage. The extradosal pair of angles alone may be extended and will provide a sufficient anchorage for most cases. A further improvement would be the omis-

sion of the web lacing from the rib except at the regions of shear, and the improvement might be carried to the point where the upper member of the rib would be omitted over the crown and the lower member at the haunches; the reinforcement then consists of an intradosal angle over the crown and an extradosal angle over the haunches joined to the intradosal angle by shearing members where they overlap. But it is to be noted that in arches of more than one span a load on one span may tend to cause the adjacent span to rise at the crown and thus fail, but which may be resisted by a light reinforcement at the extrados above the crown.

Fig. 2 is an elevation showing an arch pointed or Gothic at the spandrel faces 14 changing to oval 13 under the middle of 20 the roadway 15. (See also Fig. 3.) The arch is constructed with Gothic ends because the spandrel loading is vertical, which calls for a curve different from that of the earth fill loading which is nearly normal. 25 A stone spandrel or railing is even more certain than a concrete spandrel to produce vertical loading, hence the advantage of Gothic end construction in such places. An icebreaker 16 extends vertically upward 30 from the conical cap 17 of the rounded end of the pier 2 and is made up of two surfaces formed to constitute a wedge that slopes back toward the arch and flattens into the spandrel wall at the coping 18.

Fig. 3 shows in cross-section an arch construction having reinforcing ribs embedded in ribs 21 of masonry. An arch drum 22 connects the ribs and is reinforced by rods 23 passing through the ribs and sagging 40 near the intrados of the drum between the ribs. The outside ribs 24 are built up to extend above the level of the roadway and constitute railings for the bridge; the space between the rails up to a suitable height is 45 filled in to form the roadway. The dotted line near the springing line of Fig. 3 is to show the possible line of division in case the wing and false wall are built on footings. If the false wall is suspended this line 50 will not appear and the spandrel wall might be carried across the opening between the parts of the abutments and no wings be used. If the wings are used the openings need not be closed but the earth filling will 55 fall back into the opening to close it. This is more clearly shown in Figs. 4 and 5 where the false wall 7 and the wing 7^a are shown detached from the arch and with a space 17^a between; the earth fill falling within the 60 span of the arch itself is supported by this wing which is built to a height sufficient to hold the earth fill having a slope as shown at 11. The earth fill will of course also fall within the opening between the back of the 65 wing and the arch and will fall within the

span at a slope 12 to which the top of the false wall should be built in order to support it.

Fig. 6 shows an arch structure reinforced near both surfaces; the heavier sections 70 passing through the tension regions and the lighter sections through the compression regions; with laps of the sections made near the point of minimum bending moment. It will be understood that increase of metal 75 may be secured by adding sections at the crown and at the haunches, or by increasing the cross-section of the sections of metal. In this form of structure the abutment consists of a horizontal member and a vertical 80 member, the vertical member 7 having its back face inclined upward away from the stream and having vertical reinforcing members 26 embedded which may be joined to the longitudinal members in the body of the 85 structure. Occasional vertical masonry ribs join the ends of the two members of the abutment and have embedded tension members 27 connecting the vertical tension members 26 with the longitudinal tension members 28. In the above structure the vertical pressure is not transmitted to the base of the vertical member but is carried by the horizontal member and the horizontal thrust 90 is carried by the vertical member at its back 95 face. An advantage of this abutment is that it may be built without destroying the bearing surface of the embankment against the horizontal thrust since no back filling is required back of the abutment.

Referring next to Fig. 7 which shows in plan the wings of Fig. 3, an important feature of improvement to which my present invention pertains, resides in the reinforcing of said wings with steel rods 25 105 embedded therein extending from end to end of the wings and through the false wall of abutment between. These rods are intended to resist the thrust of the earth fill and are arranged near the upper surfaces 110 of the wings. As an additional reinforcement and bond between the wings and the abutment or end walls a substantially horizontal rod or rods may be employed, said rod or rods extending through the lower 115 portions of the wings and intermediate abutment near the level of the stream.

In Fig. 8 by extending the spandrels across the openings between the false wall and the main arch and continuing them to 38 so that the slope of the earth 39 will clear this opening a passageway may then be left through the spandrel walls 40 where they extend below the arch so as to provide a footway 41 separated from the main driveway 42. A tie rod 43 embedded in a pavement 44 extends from abutment to abutment to resist the thrust of the arch. All of this masonry, since it is tied to the abutment, helps to resist the thrust of the arch. 130

By giving this tie a sharp inclination upward as at 45 toward the abutment it is possible to induce compression in the wall 7 so that it will not be suspended from the 5 arch although it may be attached to it and kept in alignment by embedded members 26.

I claim:

1. An arch bridge comprising an arch provided with a spandrel wall and covered 10 with granular filling escaping around the end of said spandrel wall, an upright wall supported on footings intermediate the ends of the arch and extending longitudinally of the axis thereof, said wall projecting 15 outside the exposed face of the spandrel wall and supporting the escaping granular filling.

2. An arch bridge comprising an arch, an upright wall intermediate the ends of the 20 arch and extending longitudinally of the arch axis, and unsupported by the arch yet approaching closely the under surface of the arch, and a projection below the under surface of the arch conforming to the face 25 of the wall.

3. An arch bridge comprising an arch, a plurality of passageways extending entirely through under the arch, said passageways being separated by upright walls unsupported by the arch, and projecting surfaces 20 extending below the under surface of the arch to conform to said walls.

4. An arch bridge comprising an arch supported on abutments, tension members extending from abutment to abutment below the 35 opening of the arch, a pavement embedding said tension members, an upright wall resting on said pavement, and a projection projecting below the under surface of the arch and conforming to the upper end of said 40 wall said tension members having an upward bend back of the junction with said wall.

In witness whereof, I have hereunto subscribed my name in the presence of two 45 witnesses.

DANIEL B. LUTEN.
